APPARATUS FOR MAKING AN ELECTRICAL CONNECTOR

Robert M. Heller, Birmingham, Mich., assignor to Watts Electric & Mfg. Co., Birmingham, Mich., a corporation of Michigan

Original application July 2, 1956, Serial No. 595,345.
Divided and this application June 3, 1957, Serial No. 663,151

10 Claims. (Cl. 18—41)

The present invention relates generally to a tool for use during a dipping operation in liquid plastic for making a plastic boot for a tubular shell portion of a bulb socket, fuse holder or other tubular electrical receptacles, and is a division of my application filed July 2, 1956, bearing Serial Number 595,345.

One of the essential objects of the invention is to provide a tool having means, preferably in the form of a mandrel, provided with a body portion insertable into the tubular shell and having an extension insertable through an opening defined by an inwardly extending annular flange of the shell, so that said extension is exposed to and may be coated by liquid plastic during the dipping operation.

Another object is to provide a tool wherein the body portion of the mandrel is shaped to substantially fit within the shell to prevent the flow of liquid plastic between said body portion and said shell.

Another object is to provide a tool wherein the cross section of the extension adjacent said body portion is less than the area of said opening so that liquid plastic may flow through said opening into said shell and may fill the space in said opening between the edges thereof and said extension during the dipping operation.

Another object is to provide a tool wherein the cross section of the extension adjacent said body portion is less than the cross section of the body portion whereby said mandrel is provided at the juncture of said extension and said body portion with an annular shoulder adapted to be located in spaced relation to said flange so that liquid plastic flowing through said opening into said shell may flow into and fill the space between said flange and said shoulder during the dipping operation.

Another object is to provide a tool having means for limiting insertion of the body portion of the mandrel into said shell to thereby vary the location of said shoulder relative to said flange.

Another object is to provide a tool having means for holding the body portion of the mandrel in adjusted inserted position within said shell and operable to support the shell on said mandrel.

Another object is to provide a tool that is simple in construction, economical to manufacture, and efficient in operation.

Other objects, advantages and novel details of construction of this invention will be made more apparent as this description proceeds, especially when considered in connection with the accompanying drawings wherein:

Figure 1 is a fragmentary longitudinal sectional view through the combined receptacle and plastic boot, and showing the tool in an operative position relative to the receptacle and boot.

Figure 2 is an enlarged fragmentary longitudinal sectional view through the finished product, with the tool omitted.

In the drawing, the electrical receptacle A is a bulb receiving socket having a cylindrical shell 10 connected at its forward end to a short tube 12. The shell 10 and

2

tube 12 are connected together by bending the adjacent end portion of one over a radially outwardly extending flange portion of the other to provide an annular abutment flange 14. The shell 10 is provided with a formation indicated at 16 for coaction with projections on the base of an electrical light bulb. Since these form no part of the present invention they are not illustrated or described in detail.

Adjacent its rear end, the shell 10 is provided with an outwardly projecting annular open return bent portion 18 constituting an external bead for the shell and providing an inwardly opening annular channel. The outermost side of said return bent portion extends inwardly beyond the side walls of the cylindrical shell and provides an annular radially extending flange 20 that defines an opening 21 through which an electrical conductor may extend.

To complete the receptacle A and to provide the shell with the plastic boot, the shell 10 is supported on a tool 20 comprising a mandrel B, an expandable split ring 25, and an annular stop or abutment member 26. As shown, the mandrel B has a body portion 22 shaped to fit rather closely within the shell 10 of the receptacle so as to prevent flow of liquid plastic material between the outer surface of the body portion 22 and the inner surface of the shell. The mandrel is also provided with an annular groove 24 which receives the expandable split ring 25. This split ring 25 is adapted to have a frictional grip on the inner surface of the shell 10 so as to support the receptacle on the mandrel. The annular stop or abutment member 26 is sleeved on the mandrel B and may be held in adjusted position thereon by any suitable means (not shown). Such annular stop or abutment member 26 encircles the tube 12 and is engageable with the abutment flange 14 to limit insertion of the mandrel into the shell 10. At its inner end, as seen in Figure 1, the body portion 22 of the mandrel is provided with a tapered extension 28 that extends through the opening 21 and is spaced radially inwardly from the edges thereof to permit liquid plastic material to flow inwardly of the shell.

The inner end of the body portion 22 of the mandrel projects laterally from the tapered extension 28 and constitutes an annular radial shoulder 30. The annular stop or abutment member 26 of the tool limits insertion of the mandrel in the shell 10 to a position in which the shoulder 30 is spaced substantially above the upper surface of the flange 20, to provide an annular space or chamber.

When the tool, with the receptacle in position thereon, is moved downwardly into a liquid plastic material, the plastic material provides a coating 32 on the tapered extension 28 of the mandrel, a coating 34 on the lower surface of the flange 20, a coating 36 on the outer surface of the open return bent portion 18, and a coating 40 on the outer surface of the shell 10 to a height determined by the depth of insertion into the plastic material. At the same time, the inward spacing of the tapered extension 28 of the mandrel from the inner edge of the flange 20 permits the plastic material to flow around the tapered extension 28 into the annular space between the shoulder 30 of the mandrel and the upper surface of the flange 20, and thence into the inwardly opening annular channel provided by the open return bent portion 18 to form a relatively thick annular anchorage portion 42. Preferably, the shoulder 30 is located so that the anchorage portion 42 has a thickness substantially greater, and preferably several times greater, than the coating portions 32, 34, 36 and 40. In addition, it will be observed that the plastic material forms an annular connector portion 44 extending through the opening 21, overlying the inner edge of the flange 20, and serving to connect the integral outer coating por-

tions 32, 34, 36 and 40 respectively to the annular anchorage portion 42. This connector portion 44 serves the additional function of protecting the electrical conductor from engagement with the inner edge of the flange 20, and together with the tapered sleeve produced by the coating 32 when the mandrel is withdrawn, provides a completely insulated path for the electrical conductor into the interior of the receptacle.

The tapered sleeve portion produced by the coating 32 at its outer end is designed to engage tightly the insulation on the electrical conductor, and thus the plastic boot provides a perfect seal preventing entry of foreign material into the receptacle or bulb socket from its rear end.

The boot described above is unitary and is firmly united to the shell 10, particularly by the provision of the internal annular anchorage portion 42.

Many different plastic materials are suitable for the purpose but excellent results have been obtained when the plastic boot is formed by dipping in a vinyl plastic. This material is flexible and resilient and at the same time exhibits substantial strength so as to produce a rugged booted receptacle adapted for general use.

The drawings and the foregoing specification constitute a description of the improved booted electrical receptacle in such full, clear, concise and exact terms as to enable any person skilled in the art to practice the invention, the scope of which is indicated by the appended claims.

What I claim as my invention is:

1. A tool for use during a dipping operation in liquid plastic for making a plastic boot for a tubular electrical receptacle having a tubular shell portion provided at one end with an outwardly projecting annular abutment flange and provided at its other end with an inwardly extending annular flange defining an opening for an electrical conductor; comprising a mandrel having a substantially cylindrical body portion insertable into said tubular receptacle and having an axial extension insertable through said opening so that said extension is exposed to and may be coated by liquid plastic during the dipping operation, said body portion being shaped to substantially fit within the tubular shell portion of said receptacle to prevent the flow of liquid plastic between said body portion and said shell portion, the cross section of said extension adjacent said body portion being less than the area of said opening so that liquid plastic may flow through said opening into said shell portion and may fill the space in said opening between the edges thereof and said extension during the dipping operation, the cross section of said extension adjacent said body portion also being less than the cross section of said body portion whereby said mandrel is provided at the juncture of said extension and said body portion with an annular shoulder adapted to be located in spaced relation to said flange so that liquid plastic flowing through said opening into said shell portion may flow into the fill the space between said flange and said shoulder during the dipping operation, said body portion being provided exteriorly thereof intermediate its ends with an annular groove, means for holding the body portion of said mandrel in inserted position within said receptacle and operable to support the receptacle on said mandrel, including an expansible split ring engaging the annular groove in said body portion and frictionally gripping the inner surface of said shell portion, and means for limiting insertion of the body portion of said mandrel into the shell portion of the receptacle to thereby vary the location of said shoulder relative to said flange, including an annular abutment member adjustably sleeved upon the body portion of said mandrel and engageable with the annular abutment flange aforesaid.

2. A tool for use during a dipping operation in liquid plastic for making a plastic boot for a tubular shell of an electrical receptacle having at one end an outwardly

projecting annular abutment flange and having at its other end an inwardly extending annular flange defining an opening for an electrical conductor; comprising a mandrel having a substantially cylindrical body portion insertable into said tubular shell and having an axial extension insertable through said opening so that said extension is exposed to and may be coated by liquid plastic during the dipping operation, said body portion being shaped to substantially fit within said tubular shell to prevent the flow of liquid plastic between said body portion and said tubular shell, the cross section of said extension adjacent said body portion being less than the area of said opening so that liquid plastic may flow through said opening into said shell and may fill the space in said opening between the edges thereof and said extension during the dipping operation, the cross section of said extension adjacent said body portion also being less than the cross section of said body portion whereby said mandrel is provided at the juncture of said extension and said body portion with an annular shoulder adapted to be located in spaced relation to said flange so that liquid plastic flowing through said opening into said tubular shell may flow into and fill the space between said flange and said shoulder during the dipping operation, means for holding the body portion of said mandrel in inserted position within said shell and operable to support the shell on said mandrel, including expansible means between and engaging the body portion of said mandrel and said shell, and means for limiting insertion of the body portion of said mandrel into said shell to thereby vary the location of said shoulder relative to said flange including an annular abutment member adjustably sleeved upon the body portion of said mandrel and engageable with the annular abutment flange aforesaid.

3. A tool for use during a dipping operation in liquid plastic for making a plastic boot for a tubular shell of an electrical receptacle having at one end an outwardly projecting annular abutment flange and having at its other end an inwardly extending annular flange defining an opening for an electrical conductor; comprising a mandrel having a substantially cylindrical body portion insertable into said tubular shell and having an axial extension insertable through said opening so that said extension is exposed to and may be coated by liquid plastic during the dipping operation, said body portion being shaped to substantially fit within said tubular shell to prevent the flow of liquid plastic between said body portion and said tubular shell, the cross section of said extension adjacent said body portion being less than the area of said opening so that liquid plastic may flow through said opening into said shell and may fill the space in said opening between the edges thereof and said extension during the dipping operation, the cross section of said extension adjacent said body portion also being less than the cross section of said body portion whereby said mandrel is provided at the juncture of said extension and said body portion with an annular shoulder adapted to be located in spaced relation to said flange so that liquid plastic flowing through said opening into said tubular shell may flow into and fill the space between said flange and said shoulder during the dipping operation.

4. A tool for use during a dipping operation in liquid plastic for making a plastic boot for a tubular shell of an electrical receptacle having at one end an outwardly projecting annular abutment flange and having at its other end an inwardly extending annular flange defining an opening for an electrical conductor; comprising a mandrel having a substantially cylindrical body portion insertable into said tubular shell and having an axial extension insertable through said opening so that said extension is exposed to and may be coated by liquid plastic during the dipping operation, said body portion being shaped to substantially fit within said tubular shell to prevent the flow of liquid plastic between said body por-

tion and said tubular shell, the cross section of said extension adjacent said body portion being less than the area of said opening so that liquid plastic may flow through said opening into said shell and may fill the space in said opening between the edges thereof and said extension during the dipping operation, the cross section of said extension adjacent said body portion also being less than the cross section of said body portion whereby said mandrel is provided at the juncture of said extension and said body portion with an annular shoulder adapted to be located in spaced relation to said flange so that liquid plastic flowing through said opening into said tubular shell may flow into and fill the space between said flange and said shoulder during the dipping operation, said body portion being provided exteriorly thereof intermediate its ends with an annular groove, and means for holding the body portion of said mandrel in inserted position within said shell and operable to support the shell on said mandrel including an expansible split ring engaging the annular groove in said body portion and frictionally gripping the inner surface of said shell.

5. A tool for use during a dipping operation in liquid plastic for making a plastic boot for a tubular shell of an electrical receptacle having at one end an outwardly projecting annular abutment flange and having at its other end an inwardly extending annular flange defining an opening for an electrical conductor; comprising a mandrel having a substantially cylindrical body portion insertable into said tubular shell and having an axial extension insertable through said opening so that said extension is exposed to and may be coated by liquid plastic during the dipping operation, said body portion being shaped to substantially fit within said tubular shell to prevent the flow of liquid plastic between said body portion and said tubular shell, the cross section of said extension adjacent said body portion being less than the area of said opening so that liquid plastic may flow through said opening into said shell and may fill the space in said opening between the edges thereof and said extension during the dipping operation, the cross section of said extension adjacent said body portion also being less than the cross section of said body portion whereby said mandrel is provided at the juncture of said extension and said body portion with an annular shoulder adapted to be located in spaced relation to said flange so that liquid plastic flowing through said opening into said tubular shell may flow into and fill the space between said flange and said shoulder during the dipping operation, and means for holding the body portion of said mandrel in inserted position within said shell and operable to support the shell on said mandrel, including a member carried by the body portion of the mandrel and engaging said shell.

6. A tool for use during a dipping operation in liquid plastic for making a plastic boot for a tubular shell of an electrical receptacle having at one end an outwardly projecting annular abutment flange and having at its other end an inwardly extending annular flange defining an opening for an electrical conductor; comprising a mandrel having a substantially cylindrical body portion insertable into said tubular shell and having an axial extension insertable through said opening so that said extension is exposed to and may be coated by liquid plastic during the dipping operation, said body portion being shaped to substantially fit within said tubular shell to prevent the flow of liquid plastic between said body portion and said tubular shell, the cross section of said extension adjacent said body portion being less than the area of said opening so that liquid plastic may flow through said opening into said shell and may fill the space in said opening between the edges thereof and said extension during the dipping operation, the cross section of said extension adjacent said body portion also being less than the cross section of said body portion whereby said mandrel is provided at the juncture of said extension and said body portion with an annular shoulder adapted to be located in spaced relation to said flange so that liquid plastic flowing through

body portion with an annular shoulder adapted to be located in spaced relation to said flange so that liquid plastic flowing through said opening into said tubular shell may flow into and fill the space between said flange and said shoulder during the dipping operation, means for holding the body portion of said mandrel in inserted position within said shell and operable to support the shell on said mandrel including means carried by the body portion of the mandrel and engaging said shell, and means for limiting insertion of the body portion of said mandrel into said shell to thereby vary the location of said shoulder relative to said flange including means on the body portion of said mandrel and engageable with the annular abutment flange aforesaid.

7. A tool for use during a dipping operation in liquid plastic for making a plastic boot for a tubular shell of an electrical receptacle having at one end an outwardly projecting annular abutment flange and having at its other end an inwardly extending annular flange defining an opening for an electrical conductor; comprising a mandrel having a substantially cylindrical body portion insertable into said tubular shell and having an axial extension insertable through said opening so that said extension is exposed to and may be coated by liquid plastic during the dipping operation, said body portion being shaped to substantially fit within said tubular shell to prevent the flow of liquid plastic between said body portion and said tubular shell, the cross section of said extension adjacent said body portion being less than the area of said opening so that liquid plastic may flow through said opening into said shell and may fill the space in said opening between the edges thereof and said extension during the dipping operation, the cross section of said extension adjacent said body portion also being less than the cross section of said body portion whereby said mandrel is provided at the juncture of said extension and said body portion with an annular shoulder adapted to be located in spaced relation to said flange so that liquid plastic flowing through said opening into said tubular shell may flow into and fill the space between said flange and said shoulder during the dipping operation, means for holding the body portion of said mandrel in inserted position within said shell and operable to support the shell on said mandrel including expansible means between and engaging the body portion of said mandrel and said shell, and means for limiting insertion of the body portion of said mandrel into said shell to thereby vary the location of said shoulder relative to said flange including means on the body portion of said mandrel and engageable with the annular abutment flange aforesaid.

8. A tool for use during a dipping operation in liquid plastic for making a plastic boot for a tubular shell of an electrical receptacle having at one end an outwardly projecting annular abutment flange and having at its other end an inwardly extending annular flange defining an opening for an electrical conductor; comprising a mandrel having a substantially cylindrical body portion insertable into said tubular shell and having an axial extension insertable through said opening so that said extension is exposed to and may be coated by liquid plastic during the dipping operation, said body portion being shaped to substantially fit within said tubular shell to prevent the flow of liquid plastic between said body portion and said tubular shell, the cross section of said extension adjacent said body portion being less than the area of said opening so that liquid plastic may flow through said opening into said shell and may fill the space in said opening between the edges thereof and said extension during the dipping operation, the cross section of said extension adjacent said body portion also being less than the cross section of said body portion whereby said mandrel is provided at the juncture of said extension and said body portion with an annular shoulder adapted to be located in spaced relation to said flange so that liquid plastic flowing through

said opening into said tubular shell may flow into and fill the space between said flange and said shoulder during the dipping operation, means for limiting insertion of the body portion of said mandrel into said shell to thereby vary the location of said shoulder relative to said flange, and means for holding the body portion of said mandrel in adjusted inserted position within said shell and operable to support said shell on said mandrel.

9. A tool for use during a dipping operation in liquid plastic for making a plastic boot for a tubular shell of an electrical receptacle having at one end an outwardly projecting annular abutment flange and having at its other end an inwardly extending annular flange defining an opening for an electrical conductor; comprising a mandrel having a substantially cylindrical body portion insertable into said tubular shell and having an axial extension insertable through said opening so that said extension is exposed to and may be coated by liquid plastic during the dipping operation, said body portion being shaped to substantially fit within said tubular shell to prevent the flow of liquid plastic between said body portion and said tubular shell, the cross section of said extension adjacent said body portion being less than the area of said opening so that liquid plastic may flow through said opening into said shell and may fill the space in said opening between the edges thereof and said extension during the dipping operation, the cross section of said extension adjacent said body portion also being less than the cross section of said body portion whereby said mandrel is provided at the juncture of said extension and said body portion with an annular shoulder adapted to be located in spaced relation to said flange so that liquid plastic flowing through said opening into said tubular shell may flow into and fill the space between said flange and said shoulder during the dipping operation, and means for limiting insertion of the body portion of said mandrel into said shell

to thereby vary the location of said shoulder relative to said flange.

10. A tool for use during a dipping operation in liquid plastic for making a plastic boot for a tubular shell of an electrical receptacle having at one end an outwardly projecting annular abutment flange and having at its other end an inwardly extending annular flange defining an opening for an electrical conductor; comprising a mandrel having a substantially cylindrical body portion insertable into said tubular shell and having an axial extension insertable through said opening so that said extension is exposed to and may be coated by liquid plastic during the dipping operation, said body portion being shaped to substantially fit within said tubular shell to prevent the flow of liquid plastic between said body portion and said tubular shell, the cross section of said extension adjacent said body portion being less than the area of said opening so that liquid plastic may flow through said opening into said shell and may fill the space in said opening between the edges thereof and said extension during the dipping operation, the cross section of said extension adjacent said body portion also being less than the cross section of said body portion whereby said mandrel is provided at the juncture of said extension and said body portion with an annular shoulder adapted to be located in spaced relation to said flange so that liquid plastic flowing through said opening into said tubular shell may flow into and fill the space between said flange and said shoulder during the dipping operation, and means for holding the body portion of said mandrel in adjusted inserted position within said shell and operable to support said shell on said mandrel.
